UNITED STATES PATENT OFFICE.

SAMUEL ALSOP, OF BELLINGHAM, WASHINGTON.

DOOR CLOSER AND CHECK.

No. 900,973.

Specification of Letters Patent.

Patented Oct. 13, 1908.

Application filed January 29, 1908. Serial No. 413,202.

To all whom it may concern:

Be it known that I, SAMUEL ALSOP, a citizen of the United States; and a resident of Bellingham, in the county of Whatcom and 5 State of Washington, have invented certain new and useful Improvements in a Door Closer and Check, of which the following is a specification.

My invention relates to an improvement 10 in devices for automatically closing doors and is especially applicable for closing elevator-well-inclosure doors.

The object of my invention is to close the 15 door entirely by mechanical means and by the use of simple and durable apparatus.

The application of my invention to elevator-well-inclosure doors is illustrated in the accompanying sheet of drawings in which similar numerals refer to similar parts in the 20 two views.

Figure 1 is a plan view of the side of the inclosure in which is located the door opening, the door, and the device referred to. Fig. 2 is an elevation of the same, partly sectionalized, and viewed from the elevator well.

More specifically, 1 is the elevator-well-inclosure, 2 is the door, 3 is the door latch, 30 is the door catch, 4 and 5 are door hangers, 6 is 30 a screw eye attached to door hanger 5, 7 is a cord, one end of which is attached to screw eye 7 and passes over pulley sheave 8 and the other end of which is attached to weight 10. Sheave 8 finds bearings in a housing 9 securely fastened to the frame of the inclosure.

35 12 is a pipe secured in one corner of the inclosure by the clamps 13, 13. The lower end of the pipe is closed by the cap 15 and the upper end is finished with the coupling 11. This pipe is partly filled with some liquid 14.

40 The weight 10 is of such diameter that it may easily move within the pipe 12. The location of the pipe 12 is such beneath the sheave 8 that the weight hangs within the pipe without necessarily touching the sides 45 of the same. The length of the cord 7 is such that the weight never can touch the cap 15. The height of the liquid in the pipe 12 is such that, when the weight is not in the liquid, the upper surface of the liquid stands at about

50 the point reached by the middle of the weight when at its lower limit. The diameter of the stand pipe is such as compared to the diameter and length of the weight that when the weight has reached its lower limit, 55 the liquid has risen to a point a little below

the upper end of the weight. The coupling 11 on the upper end of pipe 12 provides an expanded end for the pipe so that the weight 10 when moving in this end of the pipe may not come in contact with the extreme end of 60 the same, and thus none of the liquid clinging to the weight can be scraped off by the end of the pipe and creep over the same.

In using my invention, the operator holds the door open until he desires to have it close 65 when he simply releases the door. Assume that at such a time the door 2 occupies a position as illustrated in full lines in Figs. 1 and 2. Upon it being free to move, the weight 10 moves downward carrying the door toward the left. Before the door is entirely 70 closed, however, the weight 10 dashes into the liquid 14 which greatly reduces its velocity and thus the door 2 is slowly but positively closed without slamming, when it 75 reaches the position shown in dotted outline at 2' Fig. 2 with the latch 3' engaged with catch 30. The lower limit of the weight 10 is shown in dotted outline at 10' Fig. 2. Any liquid serves very well for use in the 80 pipe 12 provided that it does not congeal at a low temperature. In practice I prefer to use a moderately viscous oil that does not harden when exposed to the lowest temperature likely to pertain where the elevator is located. 85

Although especially designed for closing elevator doors, my device is also applicable for use in closing other doors similarly hung.

Therefore, I claim.

1. In a door closer and check, the combination of a door; a weight; means for attaching said weight to said door; a receptacle containing liquid, said weight and said receptacle being of such relative diameters as to permit the free movement of said liquid by and 90 alongside of said weight when said weight is entering, moving in or leaving said liquid; means whereby said weight enters said liquid only when said door is nearly closed; and means whereby said liquid rises around said 100 weight nearly as rapidly, above its level before said weight entered the same, as said weight descends below said level.

2. In a door closer and check, the combination of a horizontally movable door, a 105 weight having relatively a much greater length than diameter, a flexible connection, between said door and said weight, a sheave over which said flexible connection is passed a liquid containing stand pipe beneath said 110

sheave of such height that said weight does
not leave the same when said door is fully
open and of such depth that said weight does
not reach its bottom when said door is fully
closed, of such internal diameter that said
weight hangs loosely in the same, and having
an enlarged upper end.

Signed at Bellingham in the county of
Whatcom and State of Washington this
twenty-second day of January A. D. 1908. ¹⁰
SAMUEL ALSOP.
